ERNEST ANTON LEDERER, OF EAST ORANGE, NEW JERSEY, ASSIGNOR TO WESTINGHOUSE LAMP COMPANY, A CORPORATION OF PENNSYLVANIA

SCREEN GRID TUBE

Application filed December 28, 1928. Serial No. 328,911.

This invention relates to an electron discharge tube and more particularly to a tube of this nature employing a shielding electrode interposed between the anode and the control electrode.

One of the objects of the invention is to provide an effective shielding of the control electrode and the anode from capacity effects.

Another object is to produce a tube of this nature which will be simple in construction, and easy to assemble.

Another object is to produce a screen grid tube having relatively few parts.

Other objects and advantages will herein-after appear.

In accordance with my invention I construct the shielding electrode in the form of a closed box of suitable mesh or solid material having a transversely disposed partition of mesh or grid like material to separate the interior of the shielding electrode into two compartments. In one compartment the anode is located and in the other compartment the control electrode is disposed. The partition is preferably of arched or semi-cylindrical form so that the control electrode and anode may be concentrically disposed. The cathode is positioned to the side of the control electrode remote from the anode.

In order that the above and other features of the invention may be more fully understood reference will be had to the accompanying drawings in which,

Fig. 1 is a section on the line I—I of Fig. 2 of one form of mount embodying my invention and employing an indirectly heated cathode.

Fig. 2 is a section on the line II—II of Fig. 1.

Fig. 3 is a perspective view of the shielding electrode.

Fig. 4 is a perspective view of a modified construction of tube.

Fig. 5 is a perspective view of the cathode and grid assembly employing a directly heated cathode.

Fig. 6 is a sectional view of a still further modification taken on the line VI—VI of Fig. 7, and

Fig. 7 is a sectional view on the line VII—VII of Fig. 6.

The modification of the invention shown in Figures 1, 2 and 3 comprises a cathode 10, control grid 11, anode 12 and screen grid 13. The cathode is of the indirectly heated type, adapted to be heated by radiation from a separate heater element, energized by alternating current, and comprises a cylindrical metal sleeve 14 preferably of nickel, coated on the exterior with an electron emitting coating, such as the oxides of the alkaline earth metals, and having a refractory metal filament 15 disposed interiorly thereof. The construction of this form of cathode is more fully described in a co-pending application of Marden and Lederer, Serial No. 292,116, filed July 12, 1928 and entitled Electron discharge device with indirectly heated cathode.

The cylindrical metal sleeve 14 is supported between two spaced disc shaped insulators 16 each of which has a centrally disposed boss 17 extending into the sleeve 14. Current conducting leads 18 project through the insulating member 16 and are secured to the ends of the heating element 15. An enlargement is formed on each of the conductors 18, as by flattening thereof, which engages against the exterior face of the insulator to prevent separation of the insulators. The tension of the coiled filament element 15 is sufficient to maintain the insulators on the sleeve 14 in fixed relative position.

The control electrode 11 consists of a pair of supporting wires 20 having grid wires wound helically therearound and secured thereto. The supporting wires 20 are disposed in apertures in the insulator 16 and support the control electrode in concentric relation to the cathode.

It should be noted that the cathode 14, the heating element 15, control electrode 11 and the insulating members 16 form a unit of construction which may be assembled separately from the remaining elements of the tube.

The screen grid or shielding electrode 13 consists of a box like structure of suitable mesh material, such as nickel mesh, having the lower end open and the upper end pro-

vided with a partition 21 having a U shaped or semi-cylindrical recess 22. The screen grid is supported upon the stem 23 of the tube by support wires 24 welded to the sides thereof and connected to the wires 25 which are sealed in the press 26.

The anode consists of a semi-cylindrical plate having a depending flange 27 by which it is supported from the press, by the wires 28.

10 The construction is particularly suitable to accurate mounting, the various parts being capable of being supported in proper position while being assembled by jigs.

15 In assembling the elements upon the stem the plate 12 is temporarily supported by a jig from the heater leads 29 and welded to the support wires 28, the jig is removed and the screen grid applied over the plate and

20 held in proper spaced relation to the anode by a jig fitting on the wires 29. The support wires 24 of the screen grid electrode are then welded to the wires 25, after which the grid and cathode assembly, which was separately formed, is placed within the U shaped recess 22 and the current conducting leads 18 thereof welded to the support wires 29.

25 The current conductor 30 for the grid may be sealed through the dome of the bulb, which is not shown, while the leading-in conductors for the cathode, screen grid, heating element and the anode are all sealed through the press 26.

30 With this construction the input circuit, that is, the control electrode and lead 30 is completely shielded from the out-put circuit, including the plate and the plate lead 28, by the screen grid 13 and capacity effects therebetween are substantially eliminated.

35 The screen grid should extend well down around the press so as to prevent capacity effects between the plate leads and the lead 30 of the control electrode. To enable this to be accomplished conveniently an opening 31 is provided in the opposite side 32 of the screen grid, to accommodate the support wires 29. This is preferably accomplished by cutting and bending a portion 33 of the mesh upwardly over a strip of metal 34, the object of this construction being to prevent a reduction in the total quantity of metal at the center of the sides 32 so that the screen grid may be heated, inductively by high frequency currents without unduly heating the portion immediately above the recess 31. If desired the screen grid, with the exception of the partition 21, may be made of fine mesh or of a solid material. The partition plate 21 may be made of coarser mesh so as not to restrict the electron flow unduly between the cathode and anode.

40 In Figures 4 and 5 a modified construction is shown, which differs from the structure of Figs. 1 to 3 in the unitary control electrode and cathode assembly.

45 In Figure 4 the assembly consists of the cylindrical or tubular cathode 35, which is carried by the insulating discs 36, as in Figure 1. The control electrode comprises a single support wire 37 having a grid wire wound therearound, one end 38 of said support wire extending through an aperture in the insulating disc 36 and the opposite end being supported from a glass bead 39 by a wire 40. The glass bead is supported above the cathode by supports 41 and is provided with horizontally extending wires 42 which may be welded to the screen grid support wires 43.

50 This unitary control electrode and cathode structure, comprising the bead 39, the control electrode and the cathode may be assembled separately, and applied to the mount, as with the construction of Figure 1 the supports 41 being welded to the supports 42 and the conductors for the heating element of the cathode being welded to the conductors 44.

55 Figure 5 shows a unitary grid and cathode structure similar to that of Figure 4 but employing a filamentary cathode 45. The control electrode 46 is wound upon a support 47 slidingly engaging in an eyelet 48 depending from the glass bead 49.

60 In both the constructions in Figures 4 and 5 expansion of the control electrode is permitted by the sliding engagement of the support wire 37 or 47 in the aperture in the disc 36 or eyelet 48, respectively.

65 In Figures 6 and 7 an inverted construction is shown in which the partition 50 of the screen grid is arched over the press, the anode 51 being disposed above the partition and the control electrode and cathode assembly being disposed beneath the partition. The anode 51 is supported from a glass bead 52 carried by the support wires 53 of the screen grid 54. The leading-in conductor 55 for the anode is taken out through the dome of the bulb. The tubular cathode 5 and contained heater element is mounted between two spaced insulators 57 carried from the press of the tube, by support wires 5 which also serve as current conductors for the heating element.

70 The control electrode comprises a helix of fine wire 59 wound about support wire 6 which is also supported from the press.

75 In all of the constructions shown it will be noted that the screen grid substantially surrounds both the anode and the control electrode and the leading-in conductors thereof one of said elements being disposed on one side of the transverse partition screen and the other of said elements being disposed on the opposite side thereof, so that effective and complete screening of the control electrode and anode is obtained.

80 It is usually preferable to mount a screen grid tube in a suitable shielded box-like structure to separate the input from the output.

ut. Such shield should be so arranged that the outside shield merely forms an extension of the screen grid inside the tube.

The construction is relatively simple, involving few parts and may be readily assembled as a factory operation.

It is obvious that many changes may be made in the construction shown and described without departing from the invention and I do not desire to be limited to the specific details shown, except in accordance with the appended claims.

What is claimed is:

1. An electron discharge mount comprising a cathode, control electrode, anode and a shielding electrode, said shielding electrode comprising a box-like structure partially surrounding said other electrodes and a partition having a U-shaped recess extending transversely of said shielding electrode, said control electrode and cathode being disposed in said recess on one side of said partition and said anode being disposed on the opposite side of said partition.

2. An electron discharge mount comprising a cathode, control electrode, anode and a shielding electrode, said shielding electrode comprising a box-like structure partially surrounding said other electrodes said shielding electrode having a closed top of grid structure provided with a recess, said control electrode and cathode being disposed within said recess and said anode being disposed within said shielding electrode.

3. An electron discharge mount comprising a cathode, a control electrode, an anode horizontally disposed therein, a screen grid, least partially surrounding said other electrodes, and a partition in said screen grid having a substantially semi-cylindrical recess, said control electrode being disposed in said recess and said anode being disposed on the opposite side of said partition.

4. An electron discharge mount comprising a cathode and a control electrode therein, common insulating means supporting said cathode and control electrode, an anode supported independently of said cathode and control electrode and a screen grid partially surrounding the other electrodes, said screen grid having a partition partially encircling said control electrode and cathode and said anode being disposed on the opposite side of said partition remote from the control electrode, and being substantially parallel therewith.

5. An electron discharge mount comprising a tubular cathode therein, a heating element disposed within said cathode, insulating members at each end of said cathode serving to support the same, a control electrode, supported from said insulating members, an anode partially encircling said control electrode and a screen grid interposed between said anode and control electrode, said grid

having a portion at least partially surrounding the other electrodes.

6. An electron discharge mount comprising a hollow tubular cathode therein, insulating members extending across the ends of said cathode, a control electrode surrounding said cathode and supported between said insulating members, an anode at least partially surrounding said control electrode, a screen grid of box-like shape substantially surrounding said anode electrode, said grid having a U-shaped recess concentric with said control electrode and interposed between said anode and control electrode.

In testimony whereof, I have hereunto subscribed my name this 27th day of December, 1928.

ERNEST ANTON LEDERER.
